UNITED STATES PATENT OFFICE.

NELSON W. DALTON, OF BUFFALO, NEW YORK, ASSIGNOR TO CURTISS AEROPLANE & MOTOR CORPORATION, A CORPORATION OF NEW YORK.

DESIGN FOR AN AEROPLANE-BODY.

50,714.

Specification for Design.

Patented May 8, 1917.

Application filed February 28, 1917. Serial No. 151,571. Term of patent 14 years.

To all whom it may concern:

Be it known that I, NELSON W. DALTON, a citizen of the United States, residing at Buffalo, in the county of Erie and State of New York, have invented a new, original, and ornamental Design for an Aeroplane-Body, of which the following is a specification, reference being had to the accompanying drawings, forming part thereof.

Figure 1 is a side elevation of the body;

Fig. 2 is a top plan view;

Fig. 3 is a front end elevation.

This design comprises an elongated substantially streamline body, the rear end of which tapers gradually to an edge and the nose end of which projects forwardly and

downwardly on a slope, giving much the frontal appearance of an ungulate cone. In the vicinity of said frontal portion a cockpit is provided whereby the occupant thereof has an unobstructed observation range directly ahead and almost vertically downwardly from all sides. The sides and bottom continue rearwardly preferably in streamline form.

I claim:

The ornamental design for an aeroplane body as shown.

NELSON W. DALTON.

Witnesses:

Wm. EBALTS, Jr.,

GEO. B. ARNOLD.
